COMBINATION TABLE AND DRESSING CABINET

Alex Carlson, Spring Valley, N. Y.

Application June 18, 1932. Serial No. 618,068

7 Claims. (Cl. 45—5)

This invention relates to a combination table and dressing cabinet and has for an object to provide an improved combination article of furniture which may be used as a regular table or as a dressing cabinet or vanity.

Yet a further object of this invention is to provide a combination table and dressing cabinet which is easily and quickly convertible from one use to the other use.

10 A further object of this invention is to provide a combination table and dressing cabinet wherein if used as a table will not interfere with its use as a storage cabinet at the same time.

15 Still a further object of this invention is to provide a combination table and dressing cabinet having a plurality of compartments therein for use both as storage compartments as well as active use as part of the dressing cabinet.

20 Yet an additional object of this invention is to provide a combination table and dressing cabinet having a plurality of adjustable mirrors rigidly secured therein, which mirrors are easily 25 adjustable to a very convenient angle when the combination article of furniture is used as a dressing cabinet or vanity.

Yet an additional object of this invention is to provide an improved combination table 30 and dressing cabinet having a lighting means which is usable not only for the article of furniture which is in use as a vanity or dressing cabinet, but part of the lighting system is also available for illuminating purposes for the 35 device which is in use as a table.

With the foregoing and other objects in view, as will hereinafter become apparent, this invention comprises the constructions, combinations and arrangements of parts hereinafter set forth, disclosed and shown on the accompanying drawings. In these drawings,

Figure 1 is a side elevation of the combination table and dressing cabinet,

40 Figure 2 is an end view of same, showing dotted position of mirror held in place by chain.

Figure 3 is a side elevation of the compartment, the two foremost doors being opened.

45 Figure 4 is a side elevation of the compartment, all three doors being opened showing shaving mirror on back of middle door, other mirror shown in vertical position being attached on rear door.

Figure 5 is a sectional view taken on line 50 5—5 of Figure 1,

Figure 6 is a plan view of the device used as a table.

Figure 7 is a side elevation of same showing one side raised in dotted position when only one-half of the table is used.

Figure 8 is a sectional view taken on line 8—8 of Figure 1, and

Figure 9 is a sectional view taken on line 9—9 of Figure 8.

The combination table and dressing cabinet 10 has a pair of uprights 11 rising from the base 12. Spaced about the base 12 are a plurality of supporting feet 13 and 14, the feet 13 being preferably secured adjacent the bottom of the uprights 11. The base 12 comprises two 15 similar compartments 15 and 16 separated by a center partition 17 to which covers 18 are hinged as at 19. A floor 20 for the compartments 15 and 16 also provide a floor for the base 12.

The base 12 will preferably be octagonal in 20 shape, as shown in Figure 8. Two of the sides of each compartment 15 and 16 are formed by panels 21 extending along the opposite sides of the uprights 11 up to the bottom of the level of a cabinet compartment 22.

The cabinet compartment 22 is formed by pairs of opposite side walls 23, to each of which a pair of doors 24 are hinged as at 25. The sides 23 of compartment 22 extend somewhat below the bottom 26 of compartment 22 and, secured to the bottom edge of each side 23, is an internally projecting flange 27 providing sliding rails for the extensible sliding board 28 having a handle knob 29 at opposite sides thereof so that it may be opened out in either direction. Handles 30 are also provided on each door 24. A board 31 secured to the bottom 26 of the compartment 22 provides a base for hinging thereto as at 32 a mirror frame 33 provided with a mirror 34, a handle 35 being provided on the mirror frame 33.

As will be observed from Figures 4 and 5 the hinge 32 on base 31 is spaced somewhat from the edge of bottom 26, allowing the mirror 34 to be entirely enclosed within the doors 24 of 100 compartment 22 against a projection 36 and to be swung over to a substantially 45° angle as shown in Figure 4.

An electric lamp 37 is provided in compartment 22 and controlled by a convenient switch 105 38 located on one of the panels 23, and the lamp 37 may be used to light up the compartment 22, its lighting effect being intensified by the presence of one of the mirrors 34, when the other mirror 34 is hinged over to the inclined position. 110

Above the top 39 of compartment 22 is provided a center cross beam 40 extending between the uprights 11. Hinged to opposite sides of cross beam 40 as at 41 are a pair of table sections 42. When in lowered position the table sections 42 and the cross beam 40 provide a usable table surface which is located at the proper height for table use. The table sections 42 may be hinged upwardly and rest against the uprights 11 as shown in Figure 2 in full position or may be supported at an angle therefrom by means of flexible chains 43 depending from the uprights 11, each chain 43 being provided with an eye member 44 adapted to cooperate with a corresponding hook member 45 underneath the table section 42.

Secured to the bottom of each table section 42 is a triangular support 48 to which is hinged as at 49 a mirror 46 having a handle 47. The hinges 49 will be rather stiff in operation so that the mirror 46 may be set at any desired angle or retained against the base 48 when the table leaves 42 are in table position. Another cross beam 50 extends across the top of uprights 11 bracing them together and providing a support for shelves 51 placed thereabove on opposite sides of a lamp support 52, the lamp 53 projecting from each side of the lamp support 52. The wiring for lamps 37 and 53 will be concealed within the members supporting the same in the conventional manner, and hence has not been shown on the drawings.

In operation, when the device is to be used as a table, the leaves 42 are set in the position shown in Figure 6. The lamps 53 may be used to provide illumination on the table while the shelves 51 may be used as a serving table to hold food or table articles not immediately needed.

40 When the device is to be used as a dressing cabinet or vanity, the leaves 42 are hinged upwardly to the position shown in Figures 1 or 2, and the compartment doors 24 opened and mirrors 34 placed in any desired position. When 45 in the position shown in Figure 4 it will be apparent that the two mirrors 34 with the lamps 37 will be quite convenient for make-up purposes. After raising the mirrors 34 to a horizontal position, the sliding board 28 may be 50 drawn out to a position to support small articles in temporary use.

Further uses for this combination table and dressing cabinet or vanity will be apparent from the construction and disclosure hereinbefore 55 set forth.

The novel features and the operation of this device will be apparent from the foregoing description. While the device has been shown and the structure described in detail, it is obvious 60 that this is not to be considered limited to the exact form disclosed, and that changes may be made therein within the scope of what is claimed, without departing from the spirit of the invention.

65 Having thus set forth and disclosed the nature of this invention, what is claimed is:

1. A combination table and dressing cabinet comprising a compartment base, a pair of uprights secured to said base, a cross beam extending between said uprights, a compartment secured to said uprights beneath said cross beam, a pair of table leaves hinged to said cross beam, said compartment supporting said table leaves in lowered table position, a mirror hinged to the 70 bottom of each table leaf, and flexible means

depending from said uprights and adapted to hold said table leaf with said mirror at a desired angle.

2. A combination table and dressing cabinet comprising a compartment base, a pair of uprights secured to said base, a cross beam extending between said uprights, a compartment secured to said uprights beneath said cross beam, a pair of table leaves hinged to said cross beam, said compartment supporting said table leaves in lowered table position, and a second cross beam extending between said uprights at their upper end. 80

3. A combination table and dressing cabinet comprising a compartment base, a pair of uprights secured to said base, a cross beam extending between said uprights, a compartment secured to said uprights beneath said cross beam, a pair of table leaves hinged to said cross beam, said compartment supporting said table leaves in lowered table position, a pair of doors hinged to said compartment, and a third door hinged to the bottom of said compartment between said pair of doors and forming a closure with said pair of doors. 90

4. A combination table and dressing cabinet comprising a compartment base, a pair of uprights secured to said base, a cross beam extending between said uprights, a compartment secured to said uprights beneath said cross beam, a pair of table leaves hinged to said cross beam, said compartment supporting said table leaves in lowered table position, a pair of doors hinged to said compartment, a third door hinged to the bottom of said compartment between said pair of doors and forming a closure with said pair of doors, and a mirror on said third door. 105

5. A combination table and dressing cabinet comprising a compartment base, a pair of uprights secured to said base, a cross beam extending between said uprights, a compartment secured to said uprights beneath said cross beam, a pair of table leaves hinged to said cross beam, said compartment supporting said table leaves in lowered table position, a pair of doors hinged to said compartment, a third door hinged to the bottom of said compartment between said pair of doors and forming a closure with said pair of doors, a mirror on said third door, said compartment having a similar pair of doors and a third door on the opposite side thereof, and another mirror on said second third door whereby said two mirrors may be used at a different angle. 115

6. A combination table and dressing cabinet comprising a compartment base, a pair of uprights secured to said base, a cross beam extending between said uprights, a compartment secured to said uprights beneath said cross beam, a pair of table leaves hinged to said cross beam, said compartment supporting said table leaves in lowered table position, a pair of doors hinged to said compartment, a third door hinged to the bottom of said compartment between said pair of doors and forming a closure with said pair of doors, a mirror on said third door, said compartment having a similar pair of doors and a third door on the opposite side thereof, and another mirror on said second third door whereby said two mirrors may be used at a different angle, and lighting means within said compartment, said lighting means being located in alignment with said mirror means to be intensified thereby. 130

7. A combination table and vanity comprising 140

10 a compartment base, cover means hinged thereto, uprights extending from said base, a pair of cross beams between said uprights, one of said cross beams being located at the upper end of 5 said uprights, the other of said cross beams extending between said uprights at a table height, a compartment secured to said uprights beneath said middle cross beam, and a pair of table leaves hinged to said cross beam and adapted to be hinged over and supported by said compartment when in table position, and to be supported by said uprights when in raised position, and reflecting means on the bottom of said table leaves, said reflecting means being in operative 80 position when the table leaves are in upright position against said uprights.

ALEX CARLSON.
